ATTORNEY

UNITED STATES PATENT OFFICE.

GEORGE B. HURD, OF NEW YORK, N. Y.

DESIGN FOR A BOX.

SPECIFICATION forming part of Design No. 26,025, dated September 15, 1896.

Application filed January 23, 1896. Serial No. 576,601. Term of patent 3*i* years.

To all whom it may concern:

Be it known that I, GEORGE B. HURD, a citizen of the United States, and a resident of New York, in the county and State of New York, have invented and produced a new and original Design for Stationery-Boxes, of which the following is a full, clear, and exact specification.

My design consists of the box A, having the compartments *a*, *b*, and *c*. Said compartments are surrounded by the wall *d*. One of said compartments, as *a*, is formed by the division-strip *e*. Another of said compartments, as *b*, is bounded by strips *e* and *g* and the wall *d*, the line of said wall *d* extending at a right angle inwardly to the point *h* and thence extending in a parallel line to the point *i*. The remaining compartment, as *c*, is surrounded on two sides by wall *d*, 20 on a third side by strip *g*, and on the fourth

side the line of the wall is extended from the point *i* to the point *j* in a right-angular line from the wall *d*. Thence it extends in a line parallel with said wall *d* to a point *k*. The base of the box extends at right angles from the wall *d* thereof. The lines of the walls *l*, *m*, and *n* of the lid *o* conform to the lines of the wall front and ends *d* of the box, so as to envelop the same when closed.

What I claim is—

The design for a stationery-box, substantially as shown and described.

In testimony that I claim the foregoing I have hereunto set my hand this 23d day of December, 1895.

GEORGE B. HURD.

Witnesses:

JOS. V. FLYNN,
R. L. SPEHNER.
